Primary Examiner — Susan Bennett Hattan*Assistant Examiner* — Leanne Was(74) *Attorney, Agent, or Firm* — The Belles Group, P.C.(57) **CLAIM**

I claim the ornamental design for patterned glass, as shown and described.

DESCRIPTION

The FIGURE is a front view of patterned glass showing the new design.

The broken line in the FIGURE represents an unclaimed boundary of the design.

1 Claim, 1 Drawing Sheet(56)
